(57) **CLAIM**

The ornamental design for an electric toothbrush as shown and described.

DESCRIPTION

FIG. 1 is a front elevation view of an electric toothbrush showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a top-left perspective view thereof;

FIG. 8 is a bottom-right perspective view thereof;

FIG. 9 is an enlarged view of the encircled portion '9' in FIG. 2; and,

FIG. 10 is an enlarged view of the encircled portion '10' in FIG. 8.

The equal-length broken lines depict portions of the article that form no part of the claimed design.

The dash-dot lines in FIGS. 2, 8, 9 and 10 illustrate the boundaries of the enlarged view indicators and form no part of the claimed design.
